UNITED STATES PATENT OFFICE.

SYDNEY SMITH, OF LONDON, ENGLAND, ASSIGNOR TO THE WELLMAN-SEAVER-MORGAN COMPANY, OF CLEVELAND, OHIO, A CORPORATION OF OHIO.

PICK-UP AND CENTERING DEVICE FOR BILLET-HANDLING MACHINES.

Application filed March 26, 1926. Serial No. 97,536.

This invention relates to billet-handling machines and more especially to machines for transferring billets from a heating furnace to a piercing machine wherein the billet 5 is converted into a tubular blank from which seamless drawn tubing is manufactured.

It is one of the objects of this invention to provide the handling mechanism with means for automatically making a central depression in one or both ends of the billet so as to facilitate the succeeding piercing operation. It is necessary that the depression or depressions, referred to, be accurately located in the ends of the billets and it is a 10 further object of the invention to provide adjustable mechanism for forming these depressions which will accommodate the apparatus to billets of different diameters and of different lengths.

Other objects of the invention and the features of novelty will be apparent from the following description taken in connection with the accompanying drawings, of which:

Fig. 1 is an elevation of a billet-handling mechanism having my invention incorporated therein;

Fig. 2 is an enlargement of a portion of Fig. 1;

Fig. 3 is an end elevation of the apparatus illustrated in Fig. 2;

Fig. 4 is a section on the line 4—4 of Fig. 2; and

Fig. 5 is a section on the line 5—5 of Fig. 2.

Referring to the drawings, 10 indicates, generally, the trolley of an overhead crane of the type that is commonly used in steel mills for the purpose of handling ingots and billets and more especially of the type that is employed in connection with soaking pits, for the purpose of handling the ingots. The trolley 10 is usually arranged to run back and forth on a travelling bridge of which 45 the beams 11 and 12 are a part, the trolley having wheels 13 which run on rails 14. In the type of crane referred to, there is usually a revoluble vertically arranged mast 15 at the lower end of which is the mechanism for gripping and carrying the ingot or billet.

According to the present invention, the lower end of the mast 15 is formed with the horizontally projecting bracket 16 and the downwardly projecting bracket 17. The 50 bracket 16 is formed, on its opposite edges,

with gibbs 18 on which a bracket 19 is slideable. A horizontally arranged screw 20 is supported in the ears 21, on the bracket 16, and has threaded connection with the lug 22 on the slide 19 so that the slide 19 may be 60 moved back and forth on the gibbs 18 by turning the screw 20, which has a squared end 23 for that purpose.

A plunger 24 is slidably mounted in the bracket 17 and is provided with trunnions 25 on which the links 26 are pivoted. The plunger 24 has a conically shaped punch 27, in its inner end, which is adapted to engage one end of the billet, at the center thereof, and form a depression in the billet, this 70 depression subsequently serving as the means for locating the piercing tool. The bracket 19 has a spur 28 which is in alignment with the punch 27 and which may be of hemispherical form, or of conical form similar to 75 the punch 27 so as to be adapted to form a depression in the opposite end of the billet. The apparatus may be adjusted for the purpose of handling billets of different lengths by moving the bracket 19, the largest billet 80 which the apparatus, illustrated, is capable of handling, being indicated in dotted lines at 29, and the smallest being indicated at 30.

In order to properly locate the billet with 85 reference to the parts 27 and 28, I provide the V-shaped members 31 and 32, the member 31 being vertically adjustable on the bracket 19, slots 33 being provided in the member 31 and bolts 34 being provided for 90 securing the member 31 in any position to which it is adjusted. The member 32 has a threaded shank 35 which extends through the wall 36 of the member 16 and is adjustable therein and secured in position by 95 means of the nuts 37, on opposite sides of this wall.

A crosshead 38 is vertically slideable in the ways 39 and has secured thereto a vertically extending shaft 40, the upper end of 100 which is threaded, as indicated at 41, and received in a rotatable nut 42 that is driven by means of the gearing 43 by any suitable source of power, so that when said nut is rotated in one direction, the crosshead 38 is 105 lowered or when the nut is rotated in the opposite direction, the crosshead 38 is raised. Two levers 44 are fulcrumed on a horizontal shaft 45 and have forked lowered ends 46 which are pivoted to the links 26. Links 110

47 connect the upper ends of the levers 44 with trunnions 48 on the crosshead so that the levers 44 are actuated by the crosshead and, in turn, reciprocate the plunger 24.

5 In the operation of the mechanism, the mast 15 is lowered, until the members 31 and 32 rest on the billet and thereby center the latter with reference to the punch 27 and spur 28. The crosshead 38, having been previously lowered, is then raised, by means of the shaft 40, which causes the plunger 24 to move toward the billet so that the punch 27 will form the depression in the end of the billet. The mast 15 may then be lifted and 10 the billet transported to the piercing machine, or any other desired destination, and released by simply lowering the crosshead 38, which effects the withdrawal of the punch 27.

15 20 From the foregoing, it will be seen that I have provided a comparatively simple mechanism that will be efficient for the purpose of accurately forming a central depression in the end of the billet and no time will be wasted in performing this operation because it is incidental to the necessary operations of picking up the billet and transferring it to its destination.

25 While I have described what I now consider to be a preferred embodiment of my invention, it will be understood that the details of construction, illustrated and described, are subject to variation without departing from the spirit of the invention as 30 defined in the appended claims.

35 Having thus described my invention, what I claim is:

40 1. In apparatus of the class described, the combination of a lifting member, means carried by said member for positioning an ingot relative thereto, a plunger carried by said member and reciprocable in alignment with the axis of the ingot when so positioned, said plunger having a punch adapted to engage one end of the ingot and form a central depression therein, and means on 45 said member for actuating said plunger.

50 2. In apparatus of the class described, the combination of a lifting member, means carried by said member for positioning an ingot relative thereto, a plunger carried by said member and reciprocable in alignment with the axis of the ingot when so positioned, said plunger having a punch adapted to engage one end of the ingot and form a central depression therein, means on said member for actuating said plunger, and means on said member opposed to said plunger for engaging the opposite end of the ingot and cooperating with said punch to support the ingot while being transported by said apparatus.

55 3. In apparatus of the class described, the combination of a lifting member, means carried by said member for positioning an in-

got relative thereto, a plunger carried by said member and reciprocable in alignment with the axis of the ingot when so positioned, said plunger having a punch adapted to engage one end of the ingot and form 70 a central depression therein, means on said member for actuating said plunger, and a bracket adjustable on said member axially of the ingot and having means opposed to said plunger for engaging the opposite end 75 of the ingot and cooperating with said punch to support the ingot while being transported by said apparatus.

4. In apparatus of the class described, the combination of a lifting member, means carried by said member for positioning an ingot 80 relative thereto, a plunger carried by said member and reciprocable in alignment with the axis of the ingot when so positioned, said plunger having a punch adapted to engage 85 one end of the ingot and form a central depression therein, a lever fulcrumed on said member and operatively connected with said plunger to effect the reciprocation of the latter, a vertically movable actuator of said 90 lever, and a link connecting said lever and said actuator.

5. In apparatus of the class described, the combination of a lifting member, a member vertically adjustable on the lifting member 95 and adapted to engage the side of an ingot adjacent one end, a bracket adjustable on the lifting member axially of the ingot, a member vertically adjustable on said bracket and adapted to engage the side of 100 the ingot adjacent the other end to cooperate with the second-mentioned member in positioning the ingot, means reciprocable on the lifting member axially of the ingot and having a punch adapted to form a central 105 depression in one end of the ingot, means carried by said bracket for engaging the opposite end of the ingot to cooperate with said punch and support the ingot while being transported by said apparatus, and 110 means for actuating said reciprocable means.

6. In apparatus of the class described, the combination of a lifting member, a member vertically adjustable on the lifting member 115 and adapted to engage the side of an ingot adjacent one end, a bracket adjustable on the lifting member axially of the ingot, a member vertically adjustable on said bracket and adapted to engage the side of the ingot 120 adjacent the other end to cooperate with the second-mentioned member in positioning the ingot, means reciprocable on the lifting member axially of the ingot and having a punch adapted to form a central depression 125 in one end of the ingot, means carried by said bracket for engaging the opposite end of the ingot to cooperate with said punch and support the ingot while being transported 130 by said apparatus, a lever fulcrumed on

said lifting member and operatively connected with said reciprocable means, a vertically movable cross-head on said lifting member, and a link connecting said cross-head and

5 said lever.

7. In apparatus of the class described, the combination of a lifting member, a member vertically adjustable on the lifting member and adapted to engage the side of an ingot adjacent one end, a bracket adjustable on the lifting member axially of the ingot, a member vertically adjustable on said bracket and adapted to engage the side of the ingot adjacent the other end to cooperate with the 10 second-mentioned member in positioning the ingot, means reciprocable on the lifting

member axially of the ingot and having a punch adapted to form a central depression in one end of the ingot, means carried by said bracket for engaging the opposite end 20 of the ingot to cooperate with said punch and support the ingot while being transported by said apparatus, said reciprocable member having a pair of trunnions thereon, levers fulcrumed on said lifting member and 25 operatively connected with said trunnions, a vertically movable cross-head on said lifting member and links connecting said cross-head with said levers.

In testimony whereof, I hereunto affix my 30 signature.

SYDNEY SMITH.
